UNITED STATES PATENT OFFICE

171,432

DISPENSING CAP FOR CONTAINERS

Cayetano Bernabó, Buenos Aires, Argentina

Application May 31, 1952, Serial No. 19,980

Term of patent 14 years

(CL. D58—26)

To all whom it may concern:

Be it known that I, Cayetano Bernabó, a citizen of Argentina, residing at Terrada 2346, Buenos Aires, Argentina, have invented a new, original, and ornamental Design for a Dispensing Cap for Containers, of which the following is a specification, reference being had to the accompanying drawing, forming a part hereof.

In the drawing:

Fig. 1 is an elevational view of a dispensing cap for containers, showing my new design.

Fig. 2 is a top view thereof.

Fig. 3 is a perspective view thereof, taken on a reduced scale.

I claim:

The ornamental design for a dispensing cap for containers, as shown.

CAYETANO BERNABÓ.
